BADGE

Sidney C. Groeschel and Aaron G. Dawson,
Columbia, S. C.

Application October 23, 1935, Serial No. 46,376

1 Claim. (Cl. 40—1.5)

Our invention relates generally to badges, and particularly to a badge having or forming a watertight compartment and especially adapted to be worn by hunters to carry hunting license records, matches, etc. safely and conveniently and an important object of the invention is to provide an attractive and rugged device of this character which can be produced at relatively low cost.

10 Another important object of the invention is to provide a badge of the character indicated whose water-tight compartment is transparent for exposing the license card or button or plate therein.

15 Other important objects of our invention will be apparent from a reading of the following description in connection with the drawing, wherein for purposes of illustration we have shown a preferred embodiment of our invention.

In the drawing:—

20 Figure 1 is a front elevational view of the embodiment showing the use of an opaque front.

Figure 2 is a transverse vertical sectional view taken therethrough showing the use of a transparent front on the badge made of celluloid or 25 the like.

Referring in detail to the drawing, the numeral 5 generally designates the body of the badge which is annular in form and includes the side wall 6 having at its outer end the outwardly 30 turned hook flange 7, the inner end of the wall 6 being extended radially inwardly in a flange 8 which has its radially inward edge bent right angularly backwardly as indicated by the numeral 9 and then turned over to form a bead 10. 35 Both the hook flange 7 and the bead 10 act as reinforcements and add to the rigidity of the body 5 besides performing other functions to be touched upon herein.

The interior of the body 5 is the carrying 40 space of the badge for holding and carrying the license certificate or button and any other small articles which the hunter may wish to carry therein, and the front of the body 5 is closed by a transparent or translucent or opaque disk 11 45 having an inturned hook flange 12 at its circumferential edge arranged to engage and snap behind the hook flange 7 on the body 5, so as to securely assemble the window 11 on the front of the body 5. In the cases of transparent or translucent disks, the material may be celluloid, while in the case of an opaque disk, metal covered with celluloid is preferred.

A removable closure 13 is provided for securely closing the opening defined by the bead 10 and 50 the flange 8, and this closure comprises the disk

portion 14 which has a substantially right angular lateral flange 15 which terminates at its outer end in a radially outwardly extending substantially right angular flange 16 which is doubled under the flange 16 to provide a reinforcing stop to engage the extremity of the bead 10 when the closure is in the closed position illustrated in Figure 2. The doubled flange 16 also acts as the means whereby the closure 13 is withdrawn from the said opening. The closure 13 has a friction fit in the said opening, engaging 50 forcibly as it does the radially inward side of the bead 10, closely enough to prevent the ingress of water and dampness into the interior of the body 5. Any suitable type of closure achieving the 55 same or similar results may be substituted for the closure 13. The disk 11 equally securely engages the body 5 to prevent ingress of dampness and water into the interior of the body 5; whereby the contents of the body 5 including the hunter's license 20 therein are preserved.

Extending rearwardly from the flange 8 is a rigid arm 17 having a double eye 18 at its upper end containing the pin which has its opposite end pointed as indicated by the numeral 22 and engageable under a hooked detent 23 which is fastened to the flange 8 at a point diametrically opposite the member 17. Any practical pin or device to hold the badge to the clothes may be used instead. It will be noted that the pin 21 30 lies close to the back of the closure 13, so that when the pin is passed through the clothing of the hunter in securing the badge in place, the pin will push the material of the clothing against the closure 13 and thereby positively hold the 35 closure in closed position.

Although we have shown and described herein a preferred embodiment of our invention, it is to be definitely understood that we do not desire to limit the application of the invention thereto, 40 and any change or changes may be made in the materials, and in the structure and arrangement of the parts, within the spirit of the invention and the scope of the subjoined claim.

What is claimed is:—

A badge of the character described, said badge comprising an annulus having on its rear edge a radially inwardly extending annular flange with its radially inward edge defining an access opening, a transparent disk, securing means 50 fastening the peripheral edge of said disk to the front edge of said annulus, a circular pan-shaped closure for telescoping in said access opening, the rear edge of the annular wall of said closure having a laterally outwardly extending 55

flange, a pin support extending axially from said annular flange at a point radially outwardly of said access opening, a fastening pin having one end pivoted to said support, and a pin detent extending axially from said annular flange at the opposite side of said access opening for detaining the free end of the pin in closed position, said pin being only sufficiently spaced from said lat-

erally outwardly extending flange on said closure to accommodate the thickness of the cloth through which the pin is inserted in use and cause the cloth between the pin in closed position and last-mentioned flange to hold said closure in closed position.

SIDNEY C. GROESCHEL.
AARON G. DAWSON.
